(57) **CLAIM**

We claim the ornamental design for a lighting device, as shown and described.

DESCRIPTION

FIG. 1 is a top perspective view of the design.

FIG. 2 is a bottom perspective view of the design.

FIG. 3 is a left side view of the design. The right side view of is a mirror image of the left side view.

FIG. 4 is a front view of the design.

FIG. 5 is a rear view of the design.

FIG. 6 is a top view of the design.

FIG. 7 is a bottom view of the design.

FIG. 8 is a left perspective view of the design with legs extended and light head articulated.

FIG. 9 is a rear perspective view of the design with legs extended and light head articulated; and,

FIG. 10 is a top perspective view of the design with legs extended and light head articulated.

Any broken line(s) shown are for illustrative purposes only and form no part of the claimed design.
